TRANSFORMER

Original Filed Feb. 6, 1924

INVENTOR.
Arthur Atwater Kent
BY Cornelius L. Ehret

his ATTORNEY.

UNITED STATES PATENT OFFICE.

ARTHUR ATWATER KENT, OF ARDMORE, PENNSYLVANIA.

TRANSFORMER.

Application filed February 6, 1924, Serial No. 691,071. Renewed October 13, 1928.

My invention relates to transformers, such, for example, as are utilizable in radio systems, and more particularly my invention relates to radio or high frequency trans-
5 formers.

In accordance with my invention, the transformer windings are disposed, respectively, inside and outside of a hollow support, the inside winding comprising a self-
10 supporting or formed coil which is introduced into the interior of the support and there held or fixed in suitable or predetermined relation with respect to the outside winding.

15 Further in accordance with my invention, one of the windings, as the inside winding, is in the form of a polygon, preferably regular or equilateral, which at its angles or vertices engages or is attached to a wall of the support, the polygonal shape facilitating application of the winding to the support and additionally loosening the coupling between the transformer windings.

20 My invention resides in a transformer or coil structure of the character hereinafter described and claimed.

25 For an illustration of one of the various forms my invention may take, reference is to be had to the accompanying drawing, 30 in which:

Fig. 1 is a vertical sectional view, partly in elevation, of structure embodying my invention.

35 Fig. 2 is a perspective view of a self-sustaining coil or winding.

Figs. 3 and 4 are, respectively, top and bottom plan views of the structure illustrated in Fig. 1.

40 Fig. 5 is a diagrammatic view illustrating one of the relations in which my structure is utilizable.

45 Referring to the drawing, 1 is a support, preferably of insulating material, such as molded bakelite, condensite or the like, in the form of a tube or shell having, if desired, the end closure or wall 2 and provided at its base with a flange 3 provided with holes 4 to receive screws or equivalent means for securing the structure to a support or base.

50 Within the shell or hollow support is provided the ledge 5, against or adjacent which is disposed the coil 6, constituting one winding of the transformer whose other winding

7 is disposed on the exterior of the shell or support in engagement with or adjacent to 55 the external ledge 8.

The coil 6 comprises any suitable number of layers of insulated conductor, as enamel, silica or cotton-covered copper wire. In the example illustrated, there is but one 60 layer of conductor constituting a formed or self-supporting winding, the neighboring turns or convolutions being held to each other by any suitable binding material, as shellac, collodion or the like, and additional- 65 65ly held by the binding straps or tapes 9. Or the binding tapes or straps 9 alone may be utilized to hold the convolutions in fixed position with respect to each other to constitute a self-sustaining or supporting coil. 70 The conductor is first wound upon a suitable form and then the binding or holding means applied, as well understood in the art of coil forming.

75 The winding or coil 6 is polygonal in form. In the example illustrated, the coil is hexagonal, though it will be understood that it may have any other suitable or desirable number of sides, for it may be triangular, square, pentagonal, octagonal, etc. 80 The winding is preferably a regular or equilateral polygon, though when suitable or desirable the length of its sides may be unequal. The external diameter or size of the coil is preferably such that at its corners or vertices 10, preferably slightly rounded, it is substantially or approximately equal to the internal diameter of the shell or support 1, at least adjacent the region where the coil is to be held or fixed. The 90 coil 6 at its vertices 10 engages the ledge 5, and is there held or secured, as by application of any suitable binding material 11, such as collodion or equivalent.

95 The polygonal form of the coil 6 is of advantage in that it is more readily introduced into and held in the support or tube 1 than a circular coil or coil of the same shape as the cross section of the chamber within the tube or support 1. There is a 100 further advantage, particularly in a radio or high frequency transformer, that the coupling between or mutual inductance of the two windings is looser or less, since the area enclosed by the winding 6 when of polygonal 105 form is less than when circular in form, and

accordingly the number of lines of force common to or threading both coils is lessened.

The ends 12 of the coil 6 extend through 5 holes 13 in the support, each end 12 extending outwardly through a hole 13 and backwardly through the adjacent hole 13 to form on the outside of the structure a loop 14, the reentrant portions of the ends 12 then 10 extending downwardly through the base or support to which the flange 3 is secured for connecting the winding 6 in circuit.

The exterior winding 7 may be separately formed and placed upon the support 1, or 15 may be wound in place upon the support, which is slightly tapered, longitudinally, more particularly for permitting easy withdrawal of the support from the mold in which formed. The ends 15 of the winding 20 7 extend through holes to the interior of the shell and thence downwardly through the base or support to which the flange 3 is attached for connecting the winding 7 in circuit.

25 While the winding 7 is shown as applied upon the exterior of the support 1, it may also be applied upon the interior of the support 1, and in such case may be polygonal in form. It may also be polygonal in form 30 when applied upon the exterior of the support 1, in which case the winding will at its sides intermediate its vertices engage or closely approach the cylindrical or conical support 1. Or the winding 6 may be placed 35 upon the exterior of the support 1 with the winding 7 either on the exterior or interior of the support, either or both coils again being polygonal in form.

In the example illustrated, the winding 6 40 is placed adjacent one end of the winding 7, thereby further loosening the coupling, particularly when the length of the coil 6 is materially less than that of the coil 7, as is the case in the example illustrated, since a 45 relatively large ratio of transformation, as of the order of four, is utilized.

In Fig. 5 there is illustrated one of the 50 circuit arrangements in which a transformer of the character described is utilizable. It is there employed to couple the anode or plate circuit of the radio frequency amplifying audion or tube V with the grid or input circuit of the detector tube or audion VI, the circuit arrangement being one well 55 known in the radio art for receiving telegraphic or telephonic messages which are reproduced in the telephone T, which also represents generically any other translating instrument and represents also the primary winding of an audio frequency amplifier. In the example illustrated, the winding 6 is the primary and winding 7 the secondary of the radio frequency transformer.

For certain purposes, it is desirable that 60 65 the coupling between the transformer wind-

ings 6 and 7 shall be loose, as indicated in Fig. 5, and this looseness of coupling is effected not only by the radial distance apart of the windings 6 and 7, but also by the location of the relatively short winding adjacent one end of the other winding, as 7, and is further increased by the polygonal form of one or both windings.

While the ledge structure 5 may be utilized as described, it shall be understood that it 75 may be omitted, and the coil 6 secured in position without recourse to the ledge 5 or equivalent, as by cementing or otherwise attaching the vertices 10 of the coil 6 to a suitable support, which in some instances may 80 be a self-supporting coil 7, without recourse to a support 1.

It shall be further understood that the 85 position of the coil 6 with respect to the coil 7 may be other than that indicated; for example, coil 6 may be disposed mid way of the length of the coil 7.

When one of the transformer coils is circular and the other polygonal, the mean or 90 average distance between the windings of the two coils is increased, thereby effecting greater looseness of coupling; and when the polygonal coil is disposed within an outer circular coil, notwithstanding close approach of the vertices of the polygonal coil to the 95 outer coil, the mean distance between the coils is greater than the distance between the vertices and the outer coil, thereby effecting loose coupling.

What I claim is:

1. A transformer comprising primary and secondary windings and a support therefor, at least one of said windings being a polygonal coil engaging said support at a plurality of circumferentially spaced vertices between which said coil is spaced from said support.

2. A transformer comprising primary and secondary windings and a support therefor, at least one of said windings being a polygonal coil, and means securing said coil to said support at a plurality of circumferentially spaced vertices between which said coil is spaced from said support.

3. A transformer comprising primary and secondary windings and a hollow support therefor, at least one of said windings being a polygonal coil disposed within said support and in contact with said support between which said coil is spaced at its vertices from said support.

4. A transformer comprising primary and secondary windings and a support therefor, at least one of said windings being a polygonal coil comprising a plurality of turns 125 disposed side by side longitudinally of the axis of the coil, said coil in contact with said support at a plurality of circumferentially spaced vertices.

5. A transformer comprising primary and 130

- secondary windings and a support therefor, at least one of said windings being a polygonal coil comprising a plurality of turns disposed side by side longitudinally of the 5 axis of the coil, said coil approaching and attached to said support only at a plurality of circumferentially spaced vertices.
6. A transformer comprising primary and secondary windings and a support therefor, 10 at least one of said windings being a self-sustaining polygonal coil engaging said support at a plurality of circumferentially spaced vertices between which said coil is spaced from said support.
- 15 7. A transformer comprising primary and secondary windings and a support therefor, at least one of said windings being a self-sustaining polygonal coil attached to said support at a plurality of circumferentially spaced vertices between which said coil is spaced from said support.
- 20 8. A transformer comprising primary and secondary windings and a support therefor, at least one of said windings being a self-sustaining polygonal coil comprising a plurality of turns disposed side by side longitudinally of the axis of the coil, said coil in contact with said support at a plurality of circumferentially spaced vertices between 25 which said coil is spaced from said support.
- 25 9. A transformer comprising primary and secondary windings and a hollow support therefor, ledge structure on the interior of said support, and a polygonal coil disposed within said support with its vertices disposed upon said ledge structure.
- 30 10. A radio frequency transformer comprising primary and secondary windings and a hollow support therefor, one of said windings disposed on the exterior of said support, another of said windings being polygonal in form and having a plurality of turns 35 disposed side by side longitudinally of its
- axis, said polygonal winding disposed within said support with its vertices only adjacent the inner wall of said support, and means for holding said polygonal winding in position within said support. 45
11. A radio frequency transformer comprising windings for effecting coupling between output and input circuits of thermionic vacuum tubes comprising a hollow support, one of said windings disposed upon the exterior of said support, another of said windings being polygonal in form and comprising a plurality of turns disposed side by side axially of the winding, said polygonal winding disposed within said support with its vertices approaching the inner wall of said support, and means for holding said 50 polygonal winding in position with respect to said support. 55
12. A transformer comprising primary and secondary windings and a cylindrical support thereof, at least one of said windings being a polygonal coil and in contact with said support at a plurality of circumferentially spaced points between which said coil is spaced from said support. 60
13. A transformer comprising a cup-shaped member of insulating material, and primary and secondary windings disposed respectively on the interior and exterior of said member. 65
14. A transformer comprising a hollow supporting member having structure projecting inwardly from the interior wall thereof, a transformer winding disposed on the exterior of said member, and a second winding disposed interiorly thereof in position determined by said projecting structure. 70
- In testimony whereof I have hereunto affixed my signature this 4th day of February, 1924.

ARTHUR ATWATER KENT.

Patent No. 1,719,057.

Granted July 2, 1929, to

ARTHUR ATWATER KENT.

It is hereby certified that error appears in the printed specification of the above numbered patent requiring correction as follows: Page 2, line 119, claim 3, after the word "support" insert the words "at its vertices"; same page and claim, lines 120 and 121, strike out the words "at its vertices"; and that the said Letters Patent should be read with these corrections therein that the same may conform to the record of the case in the Patent Office.

Signed and sealed this 24th day of June, A. D. 1930.
